METHOD OF MANUFACTURING SEAMLESS WROUGHT IRON ANNEALING BOXES

Filed Oct. 25, 1924

Inventor:
Theodor Lammne
by *David C. Guley*
Attorney

UNITED STATES PATENT OFFICE.

THEODOR LAMMINE, OF COLOGNE-MULHEIM, GERMANY.

METHOD OF MANUFACTURING SEAMLESS WROUGHT-IRON ANNEALING BOXES.

Application filed October 25, 1924, Serial No. 745,886, and in Germany November 2, 1923.

In connection with the manufacture of cylindrical annealing boxes with an outwardly offset reinforced margin in one piece without welded seams, it has been proposed 5 to form the body of the work-piece from a block of metal by pressing and drawing. However, in carrying out this process in actual practice, especially if it was the question of making annealing boxes of large 10 diameters as are mostly used, certain difficulties arose more particularly with regard to the widening of the rolled block and the simultaneous maintaining of the closed bottom.

15 It is the object of the present invention to provide an improved method for producing an annealing box of the seamless type which will be strong and durable, the invention residing in the method and steps hereinafter 20 described in detail, of drawing out the body of the box from a sheet metal blank through a succession of die operations, and supplementing these with upsetting operations whereby a seamless box is produced presenting a thickened outwardly offset rim or 25 mouth portion.

In order to obtain the desired offset shape of the marginal portion the work-piece is treated as follows. Upon the cylindrical shell of the work-piece having been reduced to a certain diameter by drawing it through the drawing die, the work-piece is no longer drawn entirely through the die in the succeeding steps of the drawing process, but 35 the drawing operation is interrupted before the marginal portion enters through the die so that the offset marginal portion produced thereby does not only retain its previous larger diameter, but that also the effect of 40 the upsetting taking place before the drawing out and reducing, is retained. In this way the marginal portions may be given a thickness of material which is already sufficient for certain purposes.

45 In order to increase even more the wall-thickness of the offset margin remaining undrawn during the last steps of the drawing process, the margin is subjected during the drawing process or between the several steps 50 or after the drawing process has been terminated, to a special upsetting operation reducing the diameter of the margin without, however, drawing it out.

In order to allow of the invention to be 55 more readily understood it will now be de-

scribed with reference to the accompanying drawing in which:

Figs. 1 to 3 diagrammatically illustrate the course of the method in three different steps, the work-piece being shown in longitudinal axial sections.

Fig. 4 illustrates a special mode of the upsetting operation; and

Fig. 5 is a longitudinal axial section through the annealing box in its final shape.

The process is started with the sheet plate 1 which is indicated by dot and dash lines in Fig. 1. This plate is first drawn by means of a drawing stamp 3 through a draw die 2 having a suitable diameter so as to produce 70 a short cylinder 5 provided with a bottom 4. After repeating this operation several times by using dies and stamps of successively smaller diameters, the next stage of the drawing process, as shown in Fig. 2, 75 consists in drawing the work-piece by means of the stamp 7 through the hole of the die 6 to such an extent only that the marginal portion 8 remains above the die unreduced and undrawn. The drawing process is then 80 continued through several steps during which the lower cylinder portion of the work-piece is further reduced and elongated as at 12 in Fig. 5. Preferably between the several drawing operations or subsequently 85 the offset marginal portion is subjected to an upsetting operation, for instance, by means of two or more jaws 9 moved together in lateral direction as indicated by the opposed small arrows in Fig. 3 thereby effecting a reduction of the diameter of the offset marginal portion without elongating it, thus increasing its wall-thickness correspondingly.

As shown in Fig. 4, the upsetting of the 95 offset marginal portion may also be produced by placing it in an upsetting die 10, the hole of which has a tapering portion, and compressing it mainly in its longitudinal direction by means of a stamp 11 pressed 100 axially against the top edge of the margin. After finishing the upsetting operations, the exact or approximately exact final shape shown in Fig. 5, may be given to the marginal portion by pressing it by means of a 105 profile die and profile stamp.

The suspension eyes or lugs used in some cases may either be welded to the cylindrical portion of the offset margin or they may be formed from the marginal portion itself 110

by cutting away the superfluous parts of the margin which is then made of a suitable length.

Having thus described my invention, what I claim as new and desire to secure by Letters Patent, is:—

1. The method of manufacturing a seamless wrought-iron annealing box with an outwardly offset thickened and reinforced mouth portion of greater internal and external diameter than the body thereof, consisting in axially pressing a portion of a blank sheet of metal through a die so as to form a cup-shaped body and so as to leave a predetermined marginal portion of the blank undrawn, drawing out the drawn cup-shaped body by progressive stages so as to elongate while reducing in diameter and wall thickness such cup-shaped body, thereby leaving unimpaired about the mouth of the finished cup-shaped body a marginal portion of greater internal and external diameter than the body and of the original wall thickness of the sheet, and then by inward lateral compression diametrically contracting said marginal portion, without reduction of its wall thickness, from the diameter at which it is left at the cessation of the body-forming operation to a smaller diameter in which it remains of greater internal and external diameter than the drawn body.
2. The method of manufacturing a seamless wrought-iron annealing box with an outwardly offset thickened and reinforced marginal portion, consisting in axially pressing a portion of a blank sheet of metal through a die so as to form a cup-shaped body and so as to leave a predetermined marginal portion of the blank undrawn, elongating the body by progressive stages so as to draw out and reduce in diameter and wall thickness such cup-shaped body, there-

by leaving unimpaired about the mouth of the finished cup-shaped body a marginal portion of greater internal and external diameter than the body and of the original wall thickness of the sheet, and then by axial compression reducing the depth of said marginal portion and by lateral compression contracting the same without reduction of wall thickness to an internal and external diameter less than its original diameter but greater than that of the drawn body.

3. The method of manufacturing a seamless wrought-iron annealing box with an outwardly offset thickened and reinforced marginal mouth portion, consisting in axially pressing a portion of a blank sheet of metal through a die so as to form a cup-shaped body and so as to leave a marginal portion of the sheet of greater internal and external diameter than the body about the mouth of the body, drawing out the cup-shaped body so formed so as to elongate and reduce its thickness and diameter while leaving unimpaired the marginal portion of original wall thickness of the sheet, and then radially and axially contracting and reducing the depth of said marginal portion to a depth less than its original depth and to a diameter less than its original diameter but to a diameter greater internally and externally than that of the drawn body, so as to produce a mouth portion of greater thickness than the body and of uniform diameter and concentric with the body at its point of juncture therewith, and whereby the material at such point of juncture is simultaneously shaped to present a reinforced stepped formation on the inside and a smooth flaring contour on the outside of the base of the offset mouth portion.

In testimony whereof I have signed my name to this specification.

THEODOR LAMMINE.
